FIG. 2

FIG. 1 is an isometric view of a crib sheet showing my new design; and

FIG. 2 is a slightly enlarged cross sectional view on line 2-2 of FIG. 1.

The characteristic features of my new design reside in the combination on a crib sheet of a ruffle permanently secured to the upper central portion thereof circumscribing a rectangular area of the sheet so as to suggest a pillow framing member for a child's head.

I claim:

The ornamental design for a crib sheet, as shown and described.
